ABSTRACT

An overload protection circuit for an electric heating blanket is provided. A sensing element in the blanket is coupled to a gas filled tube which has a pair of contacts that are opened when an overload condition is sensed, causing a bimetallic element to open a second pair of contacts connected in series with the heating element.

GLOW SWITCH RELAY FOR BLANKET OVERHEAT CONTROL SWITCH

BACKGROUND OF THE INVENTION

Electric heating blankets are commonly constructed with a heat-sensitive sensing wire or element and a heating wire or element. One frequently encountered electric heating blanket construction consists of a flexible insulating core around which the heating wire and sensing wire are wound. The heating and sensing wires are separated by a layer of heat sensitive material. The resistance of the heat-sensitive material varies inversely with the temperature of the heating wire and this variation is sensed by the sensing wire to provide for overload protection. An insulating covering is preferably supplied over the sensing wire.

Control for a blanket of the type described is conventionally achieved by a means of a thermally sensitive switch which has a pair of contacts coupled in series with the heating wire. The sensing wire may be coupled to the control circuit of a second thermally sensitive switch which has a pair of overload contacts in series with the heating wire. The second thermal switch provides overload protection for the blanket. The bimetallic thermal control switches which are commonly used to control the operation of the overload contacts are expensive and are capable of handling only a very small amount of power. Moreover, these switches tend to be overly sensitive and are difficult to manufacture.

It is therefore an object of the present invention to provide a relatively inexpensive and uncomplicated thermal overload circuit.

It is another object of the present invention to provide an overload protection circuit for an electric blanket wherein a gaseous thermally sensitive tube controls the opening and closing of a pair of overload contacts connected in series with the heating wire of the electric blanket.

It is a further object of the present invention to provide an electric blanket control in which a gas-filled control tube is coupled in series with the sensing wire of the blanket so that the gas in the tube is ionized when the blanket is turned on causing a bimetal electrode, having a contact thereon, to heat up and to deflect towards a stationary electrode contact so that when an overload condition occurs the reduction of the resistance of the sensing wire insures that the firing electrodes of the tube are shunted by the sensing wire sufficiently to allow the bimetallic electrode to cool off; thereby breaking the electrical connection between the bimetallic electrode and the stationary cathode electrode and opening the heating wire circuit.

DESCRIPTION OF THE DRAWING

The FIGURE is a schematic diagram of an embodiment of the present invention.

TECHNICAL DESCRIPTION OF THE INVENTION

In order for an electric blanket to be suitable for personal use the blanket must be safe and easy to operate. An electric heating blanket may become overheated during use thereby creating a dangerous risk to the user of the blanket, therefore virtually all commercially available blankets provide for some form of overload protection. The various control circuits that are conventionally employed, however, are relatively expensive to manufacture and are relatively difficult to manufacture. A reliable and inexpensive overload control circuit is provided by the present invention.

An electric blanket which incorporates the present invention is indicated by the reference number 10 of the FIGURE. The electric blanket 10 is constructed in a somewhat conventional manner in that it has a heating wire 12 and a sensing wire 14 incorporated therein. The length of the sensing wire is approximately equal to one-half the length of the heating wire 12, which is shown schematically in the Figure by the two half length sections 12a and 12b. The sensing wire 14 is wound through only one half of the electric blanket 10, but unlike

most sensing wires the sensing wire 14 is able to carry enough electrical current to function as a heating wire also. The sensing wire 14 may be physically located in a portion of the heating blanket with either of the half-length segments of the heating wire in proximity to it. The resistance of the heating section which is in proximity to the sensing wire 14 is slightly different from the resistance of the other section of heating wire in order to provide for temperature equalization across the heating blanket 10.

10 The heating wire 12 is connected in series with the thermal control element 16 of the thermal switch 18 across the input voltage line. The element 16 is a conventional bimetal thermal control element that is responsive to the current that flows through the heating wire 12 and it is adjustable by the user by

15 means of a conventional adjustment screw 18c. The switch 18 causes the connection between the points 18a and 18b to be repeatedly made and broken in a cyclic manner. The length of time that the connection is made during a given time period is determined by the setting of the adjustment screw.

20 In addition to the control switch 18 an overload switch 20 must be provided to insure that an overload condition does not damage the blanket and possibly result in a dangerous condition for the user of the blanket. When the blanket 10 is

25 energized the overload switch 20 closes the heating wire circuit through the points 20a and 20b since the On-Off switch 28 is in its On position and electrical connection is also made between the points 28a and 28b. The bimetallic thermal control element 22 that controls the making and breaking of the

30 contacts of the switch 20 is coupled to the control element 26. The control element 26 is a three element glow tube which has a cathode 26a that constitutes one firing electrode, a movable temperature-sensitive arm 26b which is preferably a bimetallic element and comprises the control electrode 26c and an anode electrode 26d. The glow tube 26 is filled with an ionizable gas such as neon. When the switch 28 is turned to its On position, the circuit between the points 28a and 28b is completed and current flows through the resistors 32 and 34 which function as a voltage divider.

40 The voltage that appears at the junction point of the resistors 32 and 34 causes the gas in the tube 26 to be ionized due to the current flowing through its firing electrode path which consists of the firing electrodes 26a and 26c. The bimetallic arm 26b is then deflected towards the cathode 26a

45 and electrical connection is made between the contacts 26a and 26c which causes sufficient current to flow through the bimetallic element 22 to hold the switch 20 in its closed position so that electrical connection is made between the parts 20a and 20b. Current due to ionization then flows through the

50 sensing wire 14 and the current limiting resistor 30 while current supplied directly by the line flows through the resistor 32, the element 22 and the contacts 26a and 26c.

The sensing element 14 is made of a material which has a decreased resistance when its temperature increases. When an

55 overload condition occurs the resistance of the sensing element 14 is reduced and ionization current through the tube increases. Since a relatively constant impedance is presented to the power supply current through the element 22 and the contacts 26a and 26c therefore decreases. The bimetallic arm 26b

60 then cools off and is deflected toward the anode 26d so that the electrical connection between the electrodes 26a and 26c is broken. Ionization current will now blow between the contacts 26a and 26c and through the bimetallic element 22 but this current is not sufficient to keep the switch 20 closed and the circuit between the points 20a and 20b is therefore broken.

65 The heating wire circuit will remain open until the sensing wire 14 has cooled and its resistance is increased to the point where the current through open contacts 26a and 26c is large enough to cause the bimetallic arm 26 to again deflect sufficiently to close the connection between the electrodes 26a and 26c.

70 While a particular embodiment of the present invention has been described it is not intended that the invention be limited thereto since many modifications may be made and it is in-

tended to cover any such modification that falls within the true scope and spirit of the appended claims.

What is claimed as new and desired to be secured by Letters Patent of the United States is:

1. An overload protection circuit for an electric blanket having a heating means and a sensing means which has a resistance that decreases with increasing temperature; the sensing means being located in said blanket in proximity to said heating means and electrically coupled in parallel with said heating means, comprising means for energizing said blanket, an electronic tube filled with ionizable gas which comprises a cathode, an anode, a cathode-anode path coupled in series with said sensing means and a temperature-sensitive movable arm having a control electrode thereon, said arm being positioned in a first position when said gas in said tube is deionized so that said cathode and said control electrode are spaced apart a predetermined distance, said predetermined distance being such that ionization of said gas will result when said blanket is energized and a potential is applied across the cathode-control electrode path of said tube if the resistance of said sensing means is above a predetermined minimum value, said arm moving from said first position to a second position following ionization of said gas to hold the cathode and the control electrode in contact with each other until said blanket is de-energized or until the resistance of said sensing means decreases below said minimum value, said circuit further comprising control means coupled to said tube and having a pair of

overload contacts coupled in series with said heating means; said control means being constructed to control the opening and closing of said overload contacts in accordance with the position of said movable arm and means coupled to said tube to apply a potential across said cathode and said control electrode when said blanket is energized.

2. An overload protection circuit as set forth in claim 1 wherein said means for applying a potential across said cathode and said control electrode comprises a resistive voltage dividing network which is coupled across said heating means for supplying a voltage which is less than the potential of the input source across said cathode and said control electrode.

3. An overload protection circuit as set forth in claim 1 wherein said control means comprises a bimetallic control element that is coupled in series with said cathode-anode path and sensing means.

4. An overload protection circuit as set forth in claim 3 wherein said means for applying a potential across said cathode and said control electrode comprises a resistance voltage dividing network which has a first resistor and a second resistor that are coupled in series across said heating means for supplying the voltage developed by said second resistor across the series combination of said bimetallic control element, said cathode-anode path of said tube and said sensing means.
